Specification for Design.

Patented Apr. 3, 1917.

Application filed January 30, 1917. Serial No. 145,535. Term of patent 3½ years.

To all whom it may concern:

Be it known that I, EMIL BERGER, a citizen of the United States, residing in Brooklyn, in the county of Kings and State of New York, have invented a new, original, and ornamental Design for Embroidery, of which the following is a specification, reference being had to the accompanying drawing, forming part thereof.

The figure of the drawing is a plan view of a piece of embroidery substantially illustrating my new design.

I claim as my invention:

The ornamental design for embroidery substantially as shown.

Signed at West New York, county of Hudson and State of New Jersey, this 25th day of January, one thousand nine hundred and seventeen.

EMIL BERGER.
